DESIGN FOR A GLASS PLATE OR ARTICLE OF SIMILAR NATURE

Charles L. Fordyce, New York, N. Y., assignor to
Pitman-Dreitzer & Co., Inc., New York, N. Y.,
a corporation of New York

Application January 1, 1945, Serial No. 117,209

Term of patent 14 years

(Cl. D44—15)

To all whom it may concern:

Be it known that I, Charles L. Fordyce, a citizen of the United States of America and a resident of New York, in the county of New York and State of New York, have invented a new, original, and ornamental Design for a Glass Plate or Article of Similar Nature, of which the following is the specification, reference being had to the accompanying drawing forming a part hereof.

Figure 1 is a bottom plan view of a glass plate or article of similar nature, showing my new design.

Figure 2 is a vertical sectional view taken along line 2—2 of Figure 1.

I claim:

The ornamental design for a glass plate or article of similar nature, substantially as shown.

CHARLES L. FORDYCE.
